United States Patent Office

Des. 183,096

Patented June 24, 1958

183,096

SPECTACLE TEMPLE

Irving Hirschman, Brooklyn, N. Y.

Application December 30, 1957, Serial No. 49,071

Term of patent 7 years

(Cl. D57—1)

Fig. 1.

Fig. 2.

Fig. 3.

Fig. 1 is a front elevational view of a spectacle temple, showing my new design.

Fig. 2 is a top plan view thereof.

Fig. 3 is a rear elevational view thereof.

The dominant features of my design reside in the portions shown in full lines.

I claim:

The ornamental design for a spectacle temple, substantially as shown and described.
